UNITED STATES PATENT OFFICE.

ALBERT WANNER, JR., OF NEW YORK, N. Y.

FOLDING-LEAF TABLE.

1,274,475.

Specification of Letters Patent.

Patented Aug. 6, 1918.

Application filed January 18, 1915. Serial No. 2,794.

To all whom it may concern:

Be it known that I, ALBERT WANNER, Jr., a citizen of the United States, residing at New York city, in the county of New York and State of New York, have invented certain new and useful Improvements in Folding-Leaf Tables, of which the following is a specification.

This invention relates to tables of the class capable of being converted either to the round or the square form, and particularly to that class of folding leaf tables of this general kind in which leaves folding flatwise under the center part of the table are employed.

My principal objects are to produce a table of the kind particularly indicated above which shall be strong and durable, especially as to the frame thereof and also as to the leaves when extended, which may be converted to either the round or square form with facility and convenience, and which shall be so constructed as to insure against its leaves being accidentally moved out of the folded or extended position.

Figure 1 is a perspective view of the preferred form of the table, looking at the same from below;

Fig. 2 is a plan view;

Fig. 3 is an underneath plan view of a fragment of the table on a larger scale, the leaves being in the folded position;

Fig. 4 is a fragmentary detail illustrating the construction of the frame;

Figs. 5 and 6 are fragmental vertical sectional details showing a leaf in the extended and folded positions; and,

Fig. 7 shows one of the leaf stops.

The frame of the table shown comprises substantially vertical legs, in the present instance four in number, a corresponding number of horizontal rails connecting the several legs together, each pair of legs being connected by a rail, together with means to be described for securing the legs and rails together. Each two adjoining rails *a* are arranged with their end portions crossing each other. Each rail preferably presents a materially greater vertical than horizontal dimension, and the crossing end portions of each two adjoining rails are formed the one with an upper and the other with a lower recess *a'*, after the manner of halving, into which the rails are respectively fitted, as best shown in Fig. 4. There being four legs in the present instance the four rails are ar-

ranged in rectangular disposition, in consequence of which the outer angle formed by each two crossing rails is a right angle. Each leg *b* is in cross section rectangular, so that it will therefore fit accurately the outer angle at any of the crossings of the rails *a*. When fitted to this angle, as best shown in Fig. 3, it is secured in place by two or more screws *c* driven into the same through the extremities of the rails *a* and also by the lag screw *d* which is passed diagonally into the leg through the halved joint of the rails and also through a triangular block fitted into the inner angle formed by the rails and against whose inner surface the head of the lag screw, or a washer *f* between said head and the block, bears. The extremities of the rails are flush with corresponding vertical surfaces of the leg, and the top surfaces of the leg and rails are planed off smooth.

The table top includes a center part *g* which is polygonal in form, in the present instance being rectangular, and the segmental leaves *h*, each being attached to the side of the center part by the hinges *i* in such manner that it may stand in the same plane with and thus form an extension of the center part or be folded flatwise under the same.

At corresponding points on the several rails there are secured the hinges *j* affording vertical pivots for the leaf supporting arms *k*, which may be swung to the position shown in dotted lines in Fig. 3, in which position each arm will support the corresponding leaf extended, or to the full line position in said figure, in which position said arm is adapted to support said leaf folded, or lying substantially flat against the under side of the center part of the table, the arm for this purpose being provided in its outer face with an elongated recess *l* whose lower side forms a ledge to receive the edge of the leaf. In the folded position the arms are backed by the plate springs *m* which are attached to the rails *a* and serve to hold the arms interlocked with the leaves.

To limit the outward swing of each arm I provide on the under side of the corresponding leaf a stop *n*, and to prevent the arm from being accidentally pushed back when supporting the leaf I further provide the spring-pin *o* arranged in each arm and adapted to enter a recess *p* in the leaf when the arm is against the stop. To swing the arm inwardly, it is therefore necessary to

pull down on the spring-pin *o* until it clears the recess *p*. Spring-pin *o* and stop *n* co-operate, when the stop is engaged by the arm, to hold the latter against movement in either direction. In order to prevent the hinges *i* from being strained by attempts to lift the table by means of its extended leaves each stop *n* is formed with a laterally projecting lug *q* entering a recess *r* in the arm *k* when the latter abuts the stop and binding the parts closely against each other. Each arm *k* bears outwardly of its pivot against the under side of the center part of the table when extended and when the corresponding leaf is interlocked therewith by the means *q*—*r* the leaf is held absolutely rigid or immovable either upwardly or downwardly.

n' is a recess in the under side of the center part of the table adapted to receive the stop *n* so as to allow the leaf to fold under flat against the center part.

The table top is secured on the frame, resting flat on the flush surfaces of its legs and rails, by any desired means and in such manner that the rails are parallel with the sides of the center part of the table top. It will be observed that the form of the frame is such that it lends itself to the center part of the table top being secured thereto in such manner that the said center part will be held by the frame flat against the same in all parts thereof and so prevent it from warping.

n. The peculiar arrangement of the legs and rails obviously forms a frame that it not only exceedingly strong and durable, but, while it provides for the legs being set well outwardly from the center of the table so that it will not easily tilt when pressed upon at one side, the rails *a* are sufficiently inward from the sides of the center part to allow the leaves to swing into the folded position without interference with the rails.

In order to swing each leaf from the folded to the extended position it is a simple operation to press inwardly on the arm *k* until it clears the leaf. To return the leaf to the folded position it is necessary only to release the pin *o* from the recess *p* and

swing the arm inwardly until it clears the leaf, and thereupon simply turn the leaf under until it reaches the limit of its folded position, and the interlocking of the arm therewith occurs. In this second part of the folding operation the movement has the simple character stated because the leaf and arm present to each other wiping surfaces from the time of the initial contact of the leaf with the arm until the interlocking occurs.

Having thus fully described my invention, what I claim as new and desire to secure by Letters Patent is:—

1. In a table, the combination of a frame including several spaced legs, horizontal rails each formed of one piece of material of uniform horizontal thickness, said rails having their ends crossed and halved into each other and each leg being secured in the outer angle of a crossing of two rails and having inner surfaces thereof bearing against the outer surfaces of said two rails, and a circular top secured on the frame and including a center part having its sides parallel with the rails and leaves pivoted to the sides of the top and foldable under the same, the curved outer edge of each leaf being adapted to project in between the two adjoining legs in the folded position of said leaf.

2. A table frame including several spaced legs, horizontal rails joining the legs, each two adjoining rails having their ends crossed and halved into each other and each leg being arranged in the outer angle of a crossing of two rails, securing means extending through the end of each rail into the corresponding leg, and a securing device extending through the crossing portions of each two rails and into the corresponding leg in bisecting relation to the angle of the crossing.

In testimony whereof I affix my signature in presence of two witnesses.

ALBERT WANNER, JR.
